APPARATUS FOR PACKING MATERIALS

Eben H. Carruthers, Warrenton, Oreg.

Application March 29, 1951, Serial No. 218,209

29 Claims. (Cl. 226—96)

1

My invention relates to apparatus for packing materials.

The machine of this invention will be described primarily in connection with the packing of so-called flake and chunk packs of tuna fish. However, with adaptations and modifications, the machine may be employed in connection with the packing of other products of a semi-flowable or non-flowable nature particularly meat products. The principles of the machine may also have application in the packing of other food products such for example, as cut string beans and non-food products such as cosmetics.

Reference is made to my co-pending application Serial No. 774,626, now Patent No. 2,567,052, filed September 17, 1947, and entitled "Method and Apparatus for Packing Flake Materials."

Reference is also made to my co-pending applications Serial Nos. 39,274, filed July 17, 1948, entitled "Method of Packing Materials in Containers Particularly Fish Products and Product Produced Thereby"; 131,392, filed December 6, 1949, entitled "Hopper Construction for Food Packing Machines"; and 774,625 (now abandoned) filed September 17, 1947, entitled "Apparatus for Forming and Compressing Materials."

In my application Serial No. 774,626, I have described and claimed a method and machine for packing products particularly tuna fish in which the tuna in a flake or chunk condition is fed to the machine. The tuna is filled into pockets or cylinders which are continuously moved through a path of travel. Force is applied to the product at some point during the filling operation to fill voids, expel air and insure a substantially uniform homogeneous fill of the pockets. This may be done by a force filling of the pockets, a precompressing of the product or a combination of these actions. After the force filling operation which in practice overfills the pocket, the size of the pocket is reduced by an amount which may be adjusted and the excess trimmed or removed to bring the amount of tuna in the pocket to the desired predetermined weight to be placed in the container to be filled. Thereafter, in the case of tuna, compression forces are applied to compress the tuna into a cake or slug of the desired dimensions for deposit in the container. The tuna is of a moist oily nature and I have found that, after compression, it will retain approximately the dimensions to which it was compressed and that if the cake is made slightly smaller in diameter than the container, an annular space is provided around the cake for the reception of oil to protect the tuna during

2

retorting. Moreover, when the container is opened, the container may be inverted and the cake will usually drop out as a whole cake of approximately the dimensions to which it was compressed.

5 An object of my invention is to provide a machine, operating on the same general principles as the above described machine, which is more reliable in operation, will pack containers at a higher rate of speed, will produce a superior pack and avoids substantially any waste of tuna.

10 Another object of my invention is to provide a more efficient machine adapted to compress or form flake or chunk tuna into a cake and pack 15 such cake into a can which when opened by the user presents an attractive homogeneous appearance.

15 Another object of my invention is to provide an improved machine for packing moist flaky 20 materials or materials which do not flow readily in which a compression chamber is filled with such materials, the filling operation being accomplished in a forced or pressure manner so as to fill voids in the compression chamber and 25 expel air; thereafter the mass is trimmed to a desired volume which may be adjusted to arrive at a mass of the desired weight; and thereafter the mass is compressed to form a cake of sufficient cohesiveness and rigidity that the cake will 30 retain approximately its cake form during and after packing in a can or other container.

35 Another object of my invention is to provide an improved machine adapted to compress flake or chunk tuna or other materials including food and non-food products which are capable of being compressed into a cake or slug and pack a substantially uniform predetermined weight of such materials into a can or other container.

40 Another object of my invention is to provide an improved machine in which control of weight of the material ultimately to be placed in a container is accomplished by overfilling a chamber with the materials to be packed and then removing the excess by means which are variable during the continuous operation of the machine, thereby to control with reasonable accuracy the weight of the materials to be placed in a container.

45 My invention further contemplates an improved basic machine which by adaptation and modification may be employed to loosely fill a container with materials, a measured amount of the materials being loosely dropped or deposited in the container, and the machine being provided 50 with means for controlling or varying the weight

of product to be placed in the container without interrupting the operation of the machine.

Other objects and advantages of my invention will be set forth in the claims and will be apparent from the following description, when taken in connection with the accompanying drawings, in which:

Fig. 1 is a top plan view of the machine of my invention with the motor and variable speed reducer removed for the purpose of more clearly showing the parts;

Fig. 2 is a view similar to Fig. 1 but taken on a horizontal section such as clearly to show the pockets or cylinders in the turntable, the elements for feeding the tuna fish into the pockets and the manner in which the cans or other containers are fed to and removed from the machine;

Fig. 3 is a vertical sectional view taken substantially on the line 3—3 of Fig. 1 in the direction indicated by the arrows and showing the motor, the variable speed reducer and the driving mechanism between the speed reducer and the upper and lower turrets and turn-table;

Fig. 4 is a sectional view taken substantially on the line 4—4 of Fig. 1 in the direction indicated by the arrows, the view being taken substantially at the point of trim or removal of material to control weight, the view also showing the means for varying the amount of trim to control weight;

Fig. 5 is a perspective view showing the slugs or cakes of tuna being held by the walls of their respective pockets, the containers entering the machine beneath a shear plate into alignment with the pockets, the cake of tuna being deposited in the container and the filled containers being removed from the machine;

Fig. 6 is a view somewhat diagrammatic showing a developed layout of the machine and showing the complete functional operation as the tuna chunks or flakes progress through the machine and are deposited in the container;

Fig. 7 is a sectional view showing the mounting for one of the upper plungers or pistons, the guide therefor and the actuating cam and roller;

Fig. 8 is a view taken substantially on the line 8—8 of Fig. 7 in the direction indicated by the arrows;

Fig. 9 is a sectional view taken through one of the lower plungers or pistons showing the spring mounting therefor, the manner in which the plunger is guided and the actuating cam and its associated roller;

Fig. 10 is a sectional view taken substantially on the line 10—10 of Fig. 2; and

Fig. 11 is a view similar to Fig. 6 showing the action when the product being packed is not to be pressed into a cake, showing the means for force filling the pockets, the means for controlling weight and the means for depositing the charge of material being packed into a container.

Referring to Fig. 3, the mechanism of the machine of my invention is carried by a stationary frame main casting 11 which may be suitably secured to the floor by means not shown. Carried by the main frame is an upper rotatable turret, generally indicated by the numeral 12, and a lower rotatable turret, generally indicated by the numeral 13.

Carried by the main frame at the top thereof and rigidly secured thereto but removable therefrom is a casting 14. The casting 14, together with a removable casting 16, constitutes a gear casing and houses and supports the drive gears

for the various parts of the machine as will be presently explained.

The machine is driven by a motor 17 through a suitable speed reducer 18. Preferably 17 and 18 constitute a variable speed drive for the machine to enable the machine operator through suitable controls to vary the speed of all operations at will in a manner well known in the art to which this invention applies. The variable speed drive 17—18 is mounted on the top of the casting 16 by means of an adaptor 19 bolted thereto. The output shaft of the variable speed drive 17—18 is indicated by the numeral 21. The shaft 21 drives a main shaft 23 through a flexible coupling 22.

The main shaft 23 is mounted in suitable bearings 24 and 26 carried respectively by the castings 16 and 14. A spur gear 27 is keyed to the main shaft 23 and drives a gear 28 mounted on and keyed to a lay shaft 29. The lay shaft 29 is carried in suitable bearings 31 and 32 supported in the casting 14 and has a drive pinion 33 at its lower end keyed thereto. The drive pinion 33 mates with and drives an internal ring gear 34 which drives the upper and lower turrets in a manner which will be presently clear.

The upper turret 12 comprises a single casting which rotates about the frame structure above described as an axis. For the purpose of securing the casting 36 comprising the upper turret 12 to the internal ring gear 24, a series of screws 37 extend annularly around and between the parts so that the upper turret 12 is a rigid rotatable unit rotating with the internal ring gear 34. The main frame 11 has an accurately machined cylindrical face or barrel 41 upon which the internal machined face 42 of the upper turret 12 rides.

As shown most clearly in Fig. 1, the upper turret 12 has a plurality of vertically extending bores 43 each of which merges with a vertically extending guide slot or way 44. Each of the ways or guide slots 44 lies on a radius of the circle about the center of which the upper turret 12 rotates. In the drawings I have shown twenty-four vertically extending bores 43 for the reception of a corresponding number of pistons or plungers 46. It will be appreciated that the number of plungers employed and the number of their associated parts is optional, depending upon the design of the machine, the speed thereof and the number of operations to be performed as each plunger completes a cycle.

Referring now to Fig. 7, that view shows a section through the upper turret and one of the pistons or plungers 46 mounted in its bore 43. I have also shown in that view the means, generally indicated at 47, for guiding and actuating the pistons or plungers 46. The vertically extending slot 44 constitutes a guide or way for the reception of a guide block 48 which is carried by the piston or plunger 46. For this purpose the plunger 46 may be provided with a substantially rectangular recess 49 for the reception of the correspondingly shaped guide block 48. The guide block 48 is secured to the plunger 46 by recessed screws 51. The guide block 48 corresponds in width to the width of the guide slot 44 and serves to hold the plunger 46 against rotation in the bore 43. The guide block 48 has a bore 52 for the reception of a pin 53 upon which a roller 54 freely rotates. The pin 53 is threaded and extends through the guide block 48, the threaded end 75 receiving a nut 56 which lies in a recess 57 formed

in the plunger 46. Each of the plungers is provided with an enlarged face 55.

Referring now to Fig. 6, the rollers 54 for the upper plungers or pistons 46 ride between upper and lower cams 53 and 65. The cams 53 and 65 are formed on cam elements 59 and 60 (Fig. 3) which are mounted on the outer face of the casting 14 as indicated in the drawing. As the upper turret rotates the plungers are actuated in accordance with the cam contours.

The lower turret 13 (Fig. 3) comprises an annular casting 61 which is driven by the upper turret in a manner which will presently appear. The casting 61 has a machined face 62 which rides on the machined surface 41 of the barrel shaped portion of the main frame 11. The main frame also has an annular machined ledge 63 adapted to receive and support a rotatable bearing ring 64. The bearing ring 64 is secured to the casting 61 of the lower turret 13 by means of a series of screws 66 spaced annularly around and between the parts.

The lower turret 13 has a series of bores 67 corresponding to the number of bores in the upper turret 12. These bores are adapted to receive plunger guides 68, the purpose and functions of which will later appear. As shown most clearly in Fig. 9, the casting 61 is provided with guide slots or ways 72, the number of guide slots corresponding to the number of plunger guides employed, in this case twenty-four. As in the case of the guide slots for the upper turret, the guide slots 72 are machined on a radius of the circle about the center of which the turrets rotate.

Carried in a suitable substantially rectangular cutout 73 formed in each plunger guide 68 is a rectangular guide block 74 adapted to ride in the guide slot or way 72. Each of the guide blocks 74 is provided with suitable bores for the reception of countersunk screws 76 which are threaded into the plunger guides 68. Rotatably mounted on the end of a pin 77 is a cam roller 78 which rides between the suitable cams as will presently appear. The plunger guide 68 is provided with a recess 79 for the reception of the head of a nut 81 threaded on the end of the pin 77.

The upper and lower ends of the plunger guides 68 are provided with bearing sleeves 81 in each of which a plunger or piston 82 reciprocates. The upper end of each of the plungers or pistons 82 is enlarged to form a plunger face 83 while the lower end is decreased in diameter, the decreased end being threaded as indicated at 84. A washer 86 is interposed between a pair of nuts 87 and the lower end of the plunger guide 68. A spring 89 is interposed between the enlarged head of the plunger and the top annular surface of the plunger guide 68 as indicated at 91.

The purpose of the spring mounting of the lower plungers will presently appear. For present purposes it is sufficient to state that the lower plungers are actuated by the movement of rollers 78 as they rotate on or between cams 94 and 96 (see Fig. 6). The cams 94 and 96 are carried by the main frame casting 11. The lower cam 96 is made up of three separate cam elements 97, 98 and 99 for a purpose which will later appear (see also Figs. 4, 9 and 10).

Referring now to Fig. 3, mounted between the lower face of the upper turret 12 and the upper face of the lower turret 13 is a casting generally indicated by the numeral 101. The casting 101 includes an annular boxlike structure 102 which is provided with suitable bores for the reception

of bolts 103, the bolts extending through the casting of the upper turret 12 and the casting of the lower turret 13. It will be understood that a series of bolts 103 are employed extending annularly around and between the parts.

The casting 101 has formed therein a series of pockets, cylinders or measuring chambers 104 which are open at their upper and lower ends. It will be obvious that the number of pockets 104 formed in the casting 101 corresponds to the number of upper and lower plungers 46 and 82. The arrangement of the parts is such that the upper and lower plungers are maintained in vertical alignment with each other and in vertical alignment with the axes of the pockets or cylinders 104. While I have shown upper and lower plungers and pockets 104 which are cylindrical since tuna fish is packed in cylindrical cans, this is optional. These parts could be made rectangular if it is desired to pack materials such as pressed meats in rectangular containers.

The casting 101 is extended outward to form an apron 106 having a rim 107, suitable strengthening ribs 108 being provided to support the apron and form a rigid but relatively light casting. The apron or turn-table constitutes an important improvement over the machine of my prior above mentioned application Serial No. 774,626 and is an important factor in preventing wastage of tuna and in avoiding breaking up of the tuna into pieces smaller than desired.

It will now be understood that upon rotation of the driving pinion 33 at a speed under the control of the operator, the upper and lower turrets 35 rotate as a unit together with the apron and the pockets. During rotation of the upper and lower turrets, the plungers are actuated in accordance with the dictates of their controlling cams and move into and out of the cylinders or pockets 40 104 as indicated in Figs. 3, 5 and 6.

Keyed to the main shaft 23 (Fig. 3) is a gear 111 which meshes with a gear 112. The gear 112 is rigidly secured to a shaft 113 which is supported in bearings 116 carried by the lower and upper castings 14 and 16. The shaft extends through the top wall and has an eccentric 117 and a pulley 118 rigidly secured thereto. A connecting rod 117' reciprocates as the eccentric rotates with the shaft.

The upper end of the casting 16 is formed with an annular boss 119 which is machined so as to receive an oscillatable collar 121. A pair of angle bars 122 which preferably lie substantially at right angles to each other are preferably formed integral with the collar 121 and serve to support what might be considered a hopper or perhaps more properly an agitator structure, generally indicated by the numeral 123.

As shown in Fig. 1, the connecting rod is connected to the frame formed by the angle bars 122 by means of a pivot pin 124. Although not shown in the drawings the end of the eccentric strap and link 117' may be bifurcated to straddle the angle bar and the pin extends through the flange of the angle bar 122 into the bifurcated ends of the eccentric strap. When the shaft 113 is rotated the frame comprised of the angle bars is oscillated backward and forward around the shaft 23 as an axis.

The hopper or agitator structure 123 which is attached to the frame formed by the angle irons 122 comprises a pair of downwardly and outwardly extending angle sections 126 (see Fig. 10) attached to the frame 122-122 at 127. The semi-hopper includes a vertically extending shield 128

or rear wall having an interned lower lip. The shield extends part way circumferentially of the upper turret as will be clear from an examination of Fig. 1. The angle bars 126 extend downwardly from their point of attachment at 127 and then extend forwardly beyond the rim 107 of the apron 106. At their extended ends the angle bars 126 are secured to a semi-ring 129 as shown at 131.

The semi-ring 129, as shown in Fig. 3, is angular in cross-section and has secured thereto an annular shield 132 which may be considered the forward wall of the semi-hopper or agitating device. As will be clear from a reference to Fig. 1, the annular shield 132 lies just inside the rim 107 of the apron 106 and serves to confine the material brought to the machine by preferably a conveyor 133, as indicated in dotted lines in Figs. 1 and 3.

In my co-pending application Serial No. 131,392, filed December 6, 1949, and entitled "Hopper Construction for Food Packing Machines," I have shown a hopper construction for use in connection with a machine of the type shown in my application, Serial No. 774,626. If desired, the hopper of that application may be employed with the machine of this application with the exception of conforming the hopper of that application to a circular machine. In the hopper of this application or what might more properly be considered an agitating element, the material to be packed such as flake or chunk tuna or a mixture of chunks and flakes is discharged by the conveyor 133 on to the apron or turn-table 106 between the vertically extending annular shields or walls 128 and 132.

In Fig. 1, I have broken away the downwardly and outwardly extending angle sections 126 to show that the partial enclosure formed by the annular shields 128 and 132 is open at its ends. The purpose of this modification from a conventional hopper is, as will presently appear, so that excess material brought by the conveyor beyond that required to fill the cylindrical chambers or pockets 104 may be carried by the apron 106 in a counterclockwise direction around the machine back to the entrance end or the beginning point of filling the pockets. The omission of end walls on the semi-hopper enables free entrance and exit of the material carried by the apron.

The outer shield 132 (Fig. 2) serves as a carrier or support for a series of material directing, agitating and force filling blades 141, 142 and 143. Each of the blades 141, 142, and 143 is curved on substantially the arc of a circle and may be welded or otherwise secured to the annular shield 132. The mounting of the blades and their curvature is such that the blades are directed in a trailing manner with respect to the direction of rotation of the apron or turn-table so that material, deposited on the apron by the conveyor or returned to the entrance end of the pockets upon completion of a rotation with the apron 106, is directed inward toward the pockets, as indicated by the arrow adjacent the blade 142. Preferably only a slight clearance exists between the lower edges of the material directing blades and the surface of the rotating apron so that substantially all the material deposited on the apron or rotating therewith is directed toward the pockets as they successively pass the ends of the directing blades 141 and 142 and as they pass the material directing and force-filling blade 143. It will be appreciated that the material directing blades are oscillating about the central vertical axis of the machine

with the lower edges thereof in close spaced relation to the rotating turn-table.

In Fig. 10, I have shown a sectional view through one of the pockets 104 with the force filling end of the blade 143 directly over the pocket. In the machine of my invention the speed thereof is controlled and the rate of bringing material to the machine by the conveyor is such that a surplus of material is always available to the pockets. These facts result in the material directing blades mounding the material above the pockets. Actually, as will presently appear, the pockets are filled with an amount of material in excess of that to be placed in the containers.

While the material directing blades 141 and 142 do cause a slight force-filling of the pockets due to the fact that they cause the material to pile up or mound over the pockets, the function of the angularly disposed (see Fig. 6) inner end 20 of the directing blade 143 is to exert a downward force on the mounded material so as to cause what might be termed a compressing pressure or force-filling of the pockets. The purpose of force-filling the pockets is to eliminate voids in 25 the pockets for the purpose of securing more accurate weight control and expel air as will be more fully explained later. If desired the material directing blade 142 may be shaped like the blade 143 so as also to constitute a force-filling 30 blade.

Referring now to Fig. 3, the pulley 118 which is driven by the shaft 113 is provided with a belt 146 (Fig. 1) which extends over a pulley 147 rigid with a shaft 148 (Fig. 4). An arm 149 (Fig. 1) is 35 secured to the casting 16 as shown at 151 (Fig. 4) and extends outward beyond the circumference of the machine. The outer end of the arm is provided with an opening for the reception of a support post 152 which extends vertically downward 40 toward the base of the machine. A bracket 153 is bolted or otherwise secured to the base of the machine, extends outward with respect to the base and has an opening for the reception of the lower end of the support post 152. An arm 145 is 45 secured in any suitable manner to the support post (Fig. 4) and extends inward toward the shaft 148. The inner end has an opening for the reception of the shaft 148 and suitable bushings 154 are provided. A circular cut-off knife 155 is rigidly secured to the lower end of the shaft 148 and is preferably rotated at high speed by the means described.

It will be noted from Fig. 4 which is a view taken substantially at the point of cut-off, that the knife 155 rotates in a plane parallel with the plane of the upper circumferential edges of the pockets or cylinders 104 and substantially flush therewith. The purpose of the cut-off knife is to cut off or trim the material mounded over the tops of the pockets or cylinders so as to secure substantially accurate weight control as will be presently described. The cut-off knife 155 may be considered a trimming knife in the sense that it cuts off the material substantially flush with the tops of the cylinders or pockets and thus removes the excess material.

The top wall of the bracket 153 constitutes a platform 156 for supporting a cam element 157. The cam element 157 is circular in plan and has a cam surface 158 adjacent its outer periphery. A bolt 159 having threaded upper and lower ends extends downward through the cam element 157 and the platform 156. The bolt is held in position by the means shown at 161 and on the upper 70 end of a wing nut 162 is threaded.

The cam 97 (Fig. 4) is secured to the base 11 by means of a plurality of screws 163 and the cam 97 is provided with vertically elongated slots 164 for the reception of the screws 163. It will thus be understood that the cam 97 may be adjusted upward and downward within the limits defined by the length of the slots 164. It will also be understood that upon loosening the wing nut 162, the cam element 157 may be rotated so that a roller 166 fixed to the cam 97 will roll on the cam surface 158. Adjustment of the cam element 157 will raise or lower the cam 97. As will be clear from an examination of Fig. 9, raising the cam 97 causes each plunger or piston 82 to rise to a greater height as its corresponding roller 78 rides over the cam 97. It will also be clear that adjustment of the cam element 157 may be accomplished to raise or lower the plunger or piston 82 without interrupting the operation of the machine.

Referring now to Fig. 2, the cut-off or trimming knife 155 rotates in a counterclockwise direction. Thus any material trimmed from the tops of the pockets or cylinders is carried toward the rim 107 of the apron 106. A guard 171 which may be supported in any suitable manner as by welding it to a fixed part of the machine closely overlies the trimming knife 155 so as to insure that any material carried by the trimming knife will be discharged therefrom outwardly of the path of movement of the cylinders or pockets. This will be clear from an examination of the drawings and a consideration of the direction of rotation of the trimming knife.

Referring to Fig. 5, a pair of brackets 172 is secured to the external wall of the base of the machine by means of screws and these brackets carry a pair of support columns 173. Mounted on top of the support columns in any suitable manner as by welding is a plate 174. The plate 174 is annular in shape with its outer edge spaced somewhat inward of the rim 107 of the apron 106 (Fig. 2) and with its inner edge slightly spaced from the lower rotating turret. The plate 174 is stationary and constitutes a supporting surface for the cans or other containers during the interval when the cans are being supplied empty to the machine, while they are being filled and while they are being discharged from the machine as clearly shown in Fig. 5.

Carried by the lower turret, as shown in Fig. 5, is a series of members 176, each of which has portions 177 formed on the arc of a circle corresponding to the radius upon which the containers to be filled are formed. The adjacent members 176, as shown, provide a series of can pockets 175 corresponding in number to the number of cylinders or material pockets 104. It will be appreciated that the can pockets are positioned so that they are directly in alignment with and slightly below the material pockets 104.

A bracket 178 is secured to the plate 174, as shown in Figs. 2 and 5, and has an upwardly extending part 179. The upwardly extending part has a flange for the reception of a shear plate 181. The cans are brought to the machine by means of a can chute 182, the discharge end of which is secured by means of brackets 183 to the plate 174. The can chute has an upwardly extending part 184 which is connected to a can chute which may carry the cans from a can loft. The cans move downward through the loft can chute (not shown) into the can chute 182 which turns the cans from a position such that their axes are horizontal or substantially so to a posi-

tion such that their axes are vertical. The weight of the cans discharges successive cans onto the plate 174 and they slide forwardly between the plate 174 and the shear plate 181 and each can in turn is deposited in one of the can pockets 175.

A guide plate 186 is secured in spaced relation to the plate 174 and serves to hold the cans in the can pockets 175 while the material is being discharged from the material cylinders or pockets into the cans. The guide plate 186 has an outwardly extending guide 187 and together with a discharge bar 188 (Fig. 2) also supported in spaced relation with respect to the plate 174 combines to form a guide for the discharge of the cans from the can pockets after they are filled. It will be understood that the inner end of the guide bar 188 (Fig. 2) lies in such position as to engage the cans and cause them to be discharged from their can pockets as the pockets continue to rotate.

The operation of the machine of my invention will be more clear from an examination of Fig. 6 which in a developed layout of the machine. While the view is somewhat diagrammatic, it is believed that it will be apparent how the parts previously described function to produce the action on the material illustrated in the layout. In Fig. 6, I have indicated the major parts carried by the upper turret 12 and the major parts carried by the lower turret 13.

Chunks or flakes of tuna or a mixture of both or any other materials which may be packed by the machine are preferably brought by the conveyor 133 in a volume such as always to maintain an excess of material in the semi-hopper defined by the shields 128 and 132. The materials are deposited on the apron 106 and since the semi-hopper including the directing blades 141, 142 and 143 is oscillated backward and forward about the axis of the machine, the blades by reason of their oscillation and their curvature tend to direct the material inward toward the cylinders or material pockets 104. If the operator finds that the material is being delivered by the conveyor at too slow a rate to maintain a surplus of material, he may slow down the machine through the variable speed drive above mentioned. In practice also, the conveyor is preferably under the control of the operator so that if the materials are being supplied to the machine too rapidly, he may slow down or interrupt the operation of the conveyor or, within the limits of the speed of the machine, increase its speed to take care of the surplus material.

It will be apparent from Fig. 6 that during the interval when the material pockets are being filled, the cam 65 is holding the pistons or plungers 46 in their uppermost position and a considerable space exists above the material pockets so that the material may freely enter the pockets. Since an excess of material is constantly maintained in the semi-hopper and is directed toward the pockets, the material tends to mound up over the top of the pockets as illustrated at the left in Fig. 6.

The inner end of the material directing blade 143 constitutes a presser foot and particularly by reason of its angular position and the continued rotation of the pockets is adapted to exert pressure on the mound of material above the pocket as the pockets pass beneath it and press the mound downward into the pocket. The purpose of this action is to give the material an initial compression so that the pockets are filled substantially uniformly with material and voids.

therein are filled. The initial compression tends to expel air from the product, the purpose of which will later appear. While I have shown only one presser foot, it will be obvious that the material directing blade 142 may also be equipped with a presser foot if additional force filling of the pockets is desired.

Upon an examination of Fig. 1, it will be observed that the filling space is such that approximately seven pockets are in a position to be filled simultaneously. This insures that the material directing blades 141, 142 and 143 will fill the pockets assuming the operator also maintains an excess of material on the apron in the manner previously described.

In practice, when the plungers 82 are in their lowermost position, the capacity of the pockets is in excess of the volume of tuna to be placed in a container. In the above mentioned application Serial No. 774,626, means were provided for increasing the maximum capacity of the material pockets by adjusting the cam corresponding to the cam 99. However, this has been found unnecessary and substantially accurate weight control may be obtained by the means shown herein. The pockets having been filled with material preferably in an amount in excess of that to be placed in the containers, the rollers 78 ride on to the adjustable cam 97. Simultaneously therewith the presser foot of the material directing blade 143 is exerting a downward pressure on the material to precompress it, fill voids and expel air. Further movement of the rollers 78 along the cam 97 raises the plunger 82 to a height predetermined by the positioning of the cam 157. Each plunger 82 in turn is brought to the same predetermined height and the space between the face of the plunger 82 and the cut-off knife is thus maintained a constant. Assuming the material has been properly force-loaded into the material pockets, the voids therein are filled and the volume in the pockets between the faces 83 of the plungers 82 and the cut-off knife is a constant, then the weight of successive charges of tuna is substantially a constant.

In practice, the material pockets are continuously moving through a path of travel. The machine shown herein is part of a complete packing line which includes the cleaning of the fish, the cutting of the fish into chunks or flakes and upon completion of the filling of the cans adding oil thereto, exhausting air from the can, applying the cover and clinching and closing it. Anything which interrupts the operation of the machine slows down or interrupts the operation of the entire packing line. It is therefore important that the machine be capable of adjustment to control the weight in the can without shutting down the machine. At the discharge end of the machine, a combined inspector and checker observes the cans after they are filled. She may checkweigh every tenth or twentieth can to make sure that the cans are coming from the machines filled with the proper weight of tuna. This constant checking is necessary for the reason that the moisture content of the tuna varies which affects the weight of tuna per unit of volume.

If the checker finds the cans are being filled underweight, she signals the operator who without interrupting the operation of the machine rotates the cam 157 in a counterclockwise direction, as viewed in Fig. 4, or so that the roller 166 is at a lower position as viewed in Fig. 6 so that the plunger 82 rides to a lesser height than illustrated in Fig. 6. This increases the space between the face 83 of the plunger 82 and the cut-off knife,

thereby decreasing the amount of tuna trimmed off and increasing the weight of tuna to be later deposited in the can. If the checker finds in checking the weights of cans as they are discharged from the machine that the cans are being filled overweight, the cam 157 is rotated in a clockwise direction or the roller 166 is raised from the position shown so that the plunger 82 is raised above the position shown in Fig. 6 so as to increase the amount of trim and decrease the charge of tuna to be later deposited in the can.

After the charge of tuna has been trimmed, the lower plunger may be raised slightly further, as indicated in Fig. 6, so as to additionally pre-15 compress the material against the bottom of the rotating knife, for the purpose of aiding in driving air out of the partly compacted mass. During this interval, the upper plungers 46 are moving downward and just beyond the cut-off knife 20 both plungers enter the cylinder or pocket and start to compress the tuna therein. The springs 89 during the operation just described perform no function since they are made relatively heavy and the precompression force is relatively light 25 and insufficient to compress the springs 89 to any extent.

During the interval when the charge of tuna 30 is passing through stations 8 to 12, the tuna is compressed between the upper and lower pistons into a slug or cake of tuna. The tuna is of a relatively moist, oily nature so that it may be compressed into a cake of sufficient rigidity that it will substantially retain its shape after the compression forces are removed. During the 35 compression of the material into a cake, the springs 89 are compressed so that the pressure applied to form the cake is yielding.

In Fig. 6 I have indicated at 191 an adjustable means for raising or lowering the cam 98 to 40 increase or decrease the pressure applied to each cake as it successively passes through the compression portion of the cycle. This adjustment may also be accomplished while the machine is maintained in continuous operation and the material pockets are continuously moving through 45 their path of travel. Adjustment of the pressure of each spring individually may be accomplished by adjusting the position of the nuts 87 (Fig. 9). The purpose of the adjustment of the nuts 87 is to control the clearance between the plunger face 50 83, and the lower edge of the pocket at the point where the shear plate 181 enters between them. If the clearance is too large the effect of the shear plate is lost in that any loose piece that 55 may have dropped free of the cake will be pushed or dropped through the opening instead of being retained in the pocket.

Adjacent the thirteenth station, the lowermost piston starts to withdraw, this action being accomplished by the cams 94 and 99. The initial 60 action of these cams 94 and 99 is to withdraw the plunger guide 68 and allow the spring 89 to expand without withdrawing the plunger face 83 from the cake of material. Thereafter, at station 14 the contour of the cams 94 and 99 65 withdraws the lower plunger face from contact with the cake of material. I have found the use of the springs desirable in securing proper compression of the product. While there is some expansion of the product after the compression force is withdrawn probably due to the presence of some air in the cake, this expansion is not great and occurs entirely in an axial direction since the annular margins of the cake are confined by the walls of the cylinder.

Adjacent station 14 the lower plunger is withdrawn sufficiently to pass beneath the shear plate 181 which in practice is preferably made very thin. During the period when the lower plunger face 83 is out of contact with the cake of tuna, the cake of tuna is supported by the side walls of the cylinder or pocket plus such affinity as may exist between the upper plunger face and the cake. In moving from station 13 to station 14 the plunger is withdrawn very rapidly. Any material which may drop from the cake falls upon the shear plate 181 and is carried along on the shear plate by the lower periphery of the pockets since the space between the upper surface of the shear plate and the lower peripheral edge of the pockets is extremely slight. The material carried along on the shear plate 181 is deposited in the can so that no loss in material which might affect weight results.

As previously mentioned the precompression or force-filling of the material into the cylinders or material pockets is important, not only in obtaining accurate weight but also in at least partially expelling the air prior to compression of the material into a cake.

It will be understood that since the machine is operating at a rate which may be as high as 260 cans per minute, the time interval during which the material is compressed into a cake is extremely short. If any substantial amount of air is trapped in the cake, upon withdrawal of the lower piston, the expansion of the air is likely to blow off a piece of tuna from the cake. Such blown-off material not only affects the appearance of the cake but also may interfere with proper weight control because it may adhere to the face 83 of the lower plunger instead of being deposited on the upper surface of the shear plate and then carried into the can. However, this possibility is minimized by making the shear plate thin and adjusting nuts 87 so that the enlarged face 83 of the plunger comes in close contact with the under side of the shear plate.

As previously mentioned the cans or other containers are partly guided by the shear plate 181. As each can is successively deposited in its can pocket 175, it passes from beneath the shear plate and the upper plunger starts to move downward to deposit the slug or cake of tuna in the can.

Of particular importance in connection with the machine of my invention is the fact that the tuna is compressed into a cake of sufficient rigidity and cohesiveness that it maintains approximately the dimensions to which it was compressed. Thus the cake may be preformed to a diameter somewhat less than the diameter of the can and somewhat less than the height thereof. Thus oil put in the can at a subsequent operation substantially completely envelopes the cake of tuna so as to protect the cake from scorching during retorting or cooking. Moreover, when the cake of tuna is opened by the housewife it may be inverted and in most cases dumped onto a plate as a cake of approximately the dimensions to which it was compressed.

In Fig. 6 I have shown the cake of tuna deposited in the can by dropping the cake into it after the upper plunger gives the cake an initial push. However, more often the plunger pushes the cake into the can. In either case it is desired that the upper plunger face slightly enter the margins of the can to insure that the cake is properly deposited therein. However, it is desirable that the upper plunger not exert any pressure on the cake when it is in the can which

would destroy the marginal space above mentioned. After the plunger has forced the cake of fish into the can and starts its upward travel, the cams are contoured so that the plunger pauses momentarily with the bottom of the plunger face flush with the cylinder or pocket. This condition is shown at station 20, and is done to prevent the drawing of the slugs or cakes of tuna back into the cylinder in case the cake tends to stick to the plunger face. This dwell of the plunger face is shown by the cam contour at 192 (Fig. 6).

One fact of importance not previously stressed is that tuna is a very expensive fish costing the canner anywhere from \$300.00 to \$400.00 per ton. The control of weight and the prevention of loss during packing are of extreme importance. It will be observed that losses by the machine of my invention are maintained at a minimum. Provision is made for preventing the expansion of air from blowing off chunks of tuna after they have been compressed; any piece of tuna which may drop off the cake after the lower piston is withdrawn, is deposited on the shear plate 181 and then deposited in the can; and all material cut off by the trimming knife is deposited on the rotatable apron and confined by the rim 107 so that, as viewed in Fig. 1, the material is carried by the apron or turn-table in a counterclockwise direction and swept into a material pocket when it reaches the material directing blade 181.

In Fig. 11, I have indicated a somewhat modified form of the machine of my invention to adapt it to the packing of materials which are not to be compressed into a cake. In Fig. 11, station 1 as shown in Fig. 6 has been omitted. At station 2, the lower plunger is in a raised position and at station 3, the lower plunger is dropped down rapidly to cause a subatmospheric pressure above the plunger face to aid in drawing materials into the pockets or cylinders. A force filling of the pockets or cylinders occurs at stations 4 and 5. At stations 5 and 6 the lower plungers are raised slightly to obtain the weight control described in connection with Fig. 6, the cut-off knife 155 trimming the excess material to bring the amount of material in the pockets to the described volume and hence approximately the desired weight.

In the modified form of Fig. 11, the springs 29 may be omitted since pressure is not to be applied to the material. Since the material is not to be compressed into a cake, the plungers throughout the next few stations exert only a light pressure on the material until the fourteenth station is reached when the lower plunger is quickly withdrawn so as to pass beneath the shear plate 181 which is preferably made extremely thin. The material drops down onto the shear plate and is carried along by the margin of the pockets until the material is dropped or is pushed into the cans or containers as will be clear from an examination of the drawing and as will be clear from the previous description of the operation of the machine of Fig. 6. It will be apparent from Fig. 11 that various modifications of the cam contours may be made so as to accomplish the operation shown in Fig. 11 or other modified operation of the plungers in accordance with the material or product to be packed.

While I have shown and described the preferred method and machine of my invention, it will be apparent that various changes and modifications may be made therein, particularly in the form and relation of parts without departing

from the spirit of my invention, as set forth in the appended claims.

I claim:

1. A machine for packing materials in a container comprising, in combination, a stationary frame structure, a pair of turrets mounted one above the other on said frame structure, a member having a plurality of material receiving measuring chambers mounted between said turrets, means for filling said measuring chambers with materials, means for rotating said turrets and member through a circular path of movement about said frame structure, a plurality of plungers carried by each of said turrets, each of the plungers in the upper turret being in alignment with a plunger in the lower turret and in alignment with a measuring chamber in said member, and means for actuating said plungers as they rotate through their circular paths of movement to move them into and out of said measuring chambers and compress the materials between them.

2. A machine for packing materials in a container comprising, in combination, a stationary frame structure, a pair of turrets mounted one above the other on said frame structure, a member having a plurality of material receiving measuring chambers mounted between said turrets and having an annular material receiving table-like surface extending around said measuring chambers, means for rotating said turrets and member through a circular path of movement about said frame structure, a plurality of plungers carried by each of said turrets each of the plungers in the upper turret being in alignment with a plunger in the lower turret and in alignment with a measuring chamber in said member, and means including a plurality of cam elements carried by said frame structure for actuating said plungers as they rotate through their circular paths of movement to move them into and out of said measuring chambers and compress the materials between them.

3. A machine for packing materials in a container comprising, in combination, a stationary frame structure having a barrel shaped machined part, a pair of turrets mounted one above the other on said frame structure, each of said turrets having machined surfaces bearing upon said barrel shaped part of the frame, a member having a plurality of material receiving measuring chambers mounted between said turrets, means for rotating said turrets and member through a circular path of movement about said frame structure, a plurality of plungers carried by each of said turrets, each of the plungers in the upper turret being in alignment with a plunger in the lower turret and in alignment with a measuring chamber in said member, and means including a plurality of cam elements carried by said frame structure for actuating said plungers as they rotate through their circular paths of movement to move them into and out of said measuring chambers and compress the materials between them.

4. A machine for packing materials in a container comprising, in combination, a stationary frame structure, a pair of turrets mounted one above the other on said frame structure, a member having a plurality of material receiving measuring chamber mounted between said turrets, said member being circular in shape and constituting a material receiving turntable extending externally around said measuring chambers, means for rotating said turrets and member through a circular path of movement about

said frame structure, a plurality of plungers carried by each of said turrets, each of the plungers in the upper turret being in alignment with a plunger in the lower turret and in alignment with a measuring chamber in said member, means for actuating said plungers so they rotate through their circular paths of movement to move them into and out of said measuring chambers and compress the materials between them, and means comprising a material directing element for directing the material received from an external source and directing it inward on said turntable in a direction toward said measuring chambers.

5. A machine for packing materials in a container comprising, in combination, a stationary frame structure, a pair of turrets mounted one above the other on said frame structure, a member having a plurality of material receiving measuring chambers mounted between said turrets, said member being circular in shape and constituting a material receiving turntable, means for rotating said turrets and member through a circular path of movement about said frame structure, a plurality of plungers carried by each of said turrets, each of the plungers in the upper turret being in alignment with a plunger in the lower turret and in alignment with a measuring chamber in said member, means including a plurality of cam elements carried by said frame structure for actuating said plungers as they rotate through their circular paths of movement to move them into and out of said measuring chambers, means comprising a material directing element including a plurality of material directing blades for receiving the material deposited on said turntable and directing it inward on said turntable toward said measuring chambers, and means for oscillating said material directing element including the material directing blades about the same axis as the turntable rotates.

6. In a machine for packing materials in a container the combination of a horizontally disposed material receiving turntable having a table surface and having a plurality of material receiving measuring chambers with the table surface for receiving the material being external of the measuring chambers and a material directing assembly for receiving the material from an external source and directing it on said turntable and toward said measuring chambers, means for rotating said turntable about an axis and means for oscillating said assembly about the same axis, said assembly including upwardly extending material guiding surfaces and a plurality of material directing blades which oscillate in close spaced relation with the surface of said turntable.

7. In a machine for packing materials in a container the combination of a material receiving turntable having a plurality of material receiving measuring chambers and a material directing assembly for receiving material from an external source and directing it onto said turntable and toward said measuring chambers, means for rotating said turntable about an axis, means for oscillating said assembly, said assembly including upwardly extending material guiding surfaces and a plurality of material directing blades which oscillate in close spaced relation with the surface of said turntable, and means above the path of movement of the measuring chambers for force loading of the material into the measuring chambers.

8. A machine for packing materials in a container comprising, in combination, means for obtaining a substantially constant predetermined weight of material for deposit in each of a series of said containers comprising a series of measuring chambers movable continuously through a circular path of travel, said chambers each having fixed walls which enclose the material on all sides except for the upper and lower ends which are open, a plunger movable with each of said chambers throughout its path of travel and extending through the lower open ends of said chambers, said material being deposited in the chambers at least partly by gravity through the upper open ends of said chambers with the position of the plungers determining the volume of the chambers, means for moving said plungers into the chambers a predetermined amount to reduce the volume of the chambers which the material may occupy, means comprising a circular rotating knife past and beneath which the upper open ends of the chambers pass during movement through their circular path of travel for removing excess material, and means for moving said chambers continuously through said circular path of travel.

9. A machine for packing materials in a series of containers comprising, in combination, means for obtaining a substantially constant predetermined weight of materials for deposit in each of said series of containers comprising a series of measuring chambers movable continuously through a circular path of travel, each of said chambers having fixed walls which enclose the material on all sides except for the upper and lower ends which are open, a plunger movable with each of said chambers throughout its path of travel and extending through the lower open ends of the chambers, means for directing the material into the chambers through the upper open ends thereof, means for moving said plungers into the chambers a predetermined amount to control the volume of the chambers which the material may occupy, means comprising a circular rotatable knife past and beneath which the upper open ends of the chambers pass during movement through their circular path of travel for removing excess material, a series of plungers above said chambers movable with the chambers throughout their path of travel, means for compressing the material in each of said chambers between the upper and lower plungers into a cake of approximately predetermined weight, means for transferring the material in each of said chambers in cake form to a container, and means for moving said chambers continuously through said circular path of travel.

10. In a machine for packing materials in each of a series of containers, a member having an axis of rotation and having a series of material receiving measuring chambers, means for rotating said member about said axis to define a cycle of operation, means for filling said chambers during a portion of the cycle of operation in such manner that the material tends to mound up above the chambers, means for removing the mounded material so that the material is substantially flush with the margins of the chambers, means including a material carrying surface in connection with said member for carrying the removed material around said axis so that the removed material may be returned to the chambers at the chamber filling portion of the cycle and means for closing the bottoms

of said chambers at least while they pass through the filling portion of the cycle of operation.

11. In a machine for packing materials in each of a series of containers, an annular member having an axis of rotation and having a series of material receiving measuring chambers, means for rotating said member about said axis to define a cycle of operation, said member having a chamber filling sector through which it passes, means for filling said chambers as they pass through the chamber filling sector in such manner that the material tends to mound up above the chambers, a circular cut off knife adjacent the end of the filling sector for removing the material mounded up over the chambers, means for rotating said cut off knife, means in connection with said member for carrying the removed material around said axis back to the chamber filling sector and means for closing the bottoms of said chambers at least while they are passing through the chamber filling sector.

12. In a machine for packing materials in each of a series of containers, an annular member having an axis of rotation and having a series of material receiving measuring chambers, means for rotating said member about said axis to define a cycle of operation, said member having a chamber filling sector through which it passes, means for filling said chambers as they pass through the chamber filling sector in such manner that the material tends to mound up above the chambers, said chamber filling means including means movable independently of said annular member to direct material into said chambers, a circular cut off knife adjacent the end of the filling sector for removing the material mounded up over the chambers, means for rotating said cut off knife, means including a material carrying surface in connection with said member for carrying the removed material around said axis back to the chamber filling sector and means for closing the bottoms of said chambers at least while they are passing through the chamber filling sector.

13. A machine for packing materials in each of a series of containers comprising, in combination, a stationary frame structure having a vertical axis, a pair of turrets mounted one above the other on said frame structure, an annular member having a plurality of open ended material receiving measuring chambers mounted between said turrets, means for rotating said turrets and annular member in unison about the axis of said frame structure, a plurality of plungers carried by each of said turrets, each of the plungers in the upper turret being in alignment with a plunger in the lower turret and in alignment with a chamber in said member, means for actuating the plungers to move them into and out of said chambers as the turrets and annular member are rotated, said annular member having a chamber filling sector through which it passes, the lower plungers closing the lower ends of said chambers and the upper plungers being clear of said chambers when said member moves through the chamber filling sector, means for directing material into the chambers as they pass through the chamber filling sector in such manner that an excess of material is supplied to said chambers, means adjacent the end of said chamber filling sector for removing the excess material, and means in connection with said member for carrying the removed material around said axis back to the chamber filling sector.

14. A machine for packing materials in each of a series of containers comprising, in combination, a stationary frame structure having a vertical axis, a pair of turrets mounted one above the other on said frame structure, an annular member having a plurality of open ended material receiving measuring chambers mounted between said turrets, means for rotating said turrets and annular member in unison about the axis of said frame structure a plurality of plungers carried by each of said turrets, each of the plungers in the upper turret being in alignment with a plunger in the lower turret and in alignment with a chamber in said member, means for actuating the plungers to move them into and out of said chambers as the turrets and annular member are rotated, said annular member having a chamber filling sector and a container filling sector through which it passes, the lower plungers closing the lower ends of said chambers and the upper plungers being clear of said chambers when said member moves through the chamber filling sector, means for directing material into the chambers as they pass through the chamber filling sector in such manner that an excess of material is supplied to said chambers, means adjacent the end of said chamber filling sector for removing the excess material, means for supplying empty containers to the machine and removing them filled therefrom at the chamber filling sector, a stationary shear plate adjacent the container filling sector below the chambers and below which the lower plungers pass, and means in connection with said member for carrying the removed material around said axis back to the chamber filling sector.

15. In a machine for packing materials in a container the combination of a material receiving turntable having an external perimeter, and having a plurality of material receiving measuring chambers and a material directing assembly for receiving the material from an external source and directing it into said measuring chambers, means for rotating said turntable about an axis, and means for oscillating said assembly about the same axis and with at least the major part thereof within said external perimeter.

16. In a machine for packing materials in a container comprising the combination of a plurality of material receiving measuring chambers, a plunger above each of said measuring chambers and a plunger below each of said measuring chambers, means for rotating said measuring chambers and plungers in unison, means for moving said plungers into and out of said measuring chambers during rotation, means for yieldingly mounting at least one of said sets of plungers whereby when the plungers engage material in the measuring chambers a yielding compression force is applied on the material.

17. A machine for packing materials in containers comprising, in combination, a material receiving turntable, a series of material receiving measuring chambers carried by said turntable, means for rotating said turntable and chambers continuously through an endless path of travel part of said path including a filling station, means at the filling station for urging the material into and above said chambers in an amount in excess of that required to fill said chambers, means for trimming off said excess, means for directing said excess back onto the turntable so that it may rotate therewith back to the filling station and means for closing the

bottoms of said measuring chambers at least while they are passing through the filling station.

18. A machine in accordance with claim 17 in which the trimming means constitutes a knife and the directing means overlies the knife.

19. A machine in accordance with claim 17 in which the means for urging the material into the chambers is at least one blade which is movable backward and forward in close spaced relation to the surface of the turntable while the turntable passes beneath it.

20. A machine for packing materials in containers comprising, in combination, a material receiving turntable rotatable about a vertical axis, a series of material receiving measuring chambers having vertical side walls and open tops and bottoms rotatable with said turntable, means for rotating said turntable and chambers continuously through an endless path of travel part of said path including a filling station, said turntable having an area outwardly of the chambers upon which at least part of the material to be packed is deposited, means at the filling station for urging the material on the turntable

25 into the chambers, the material being supplied to the turntable and chambers in a quantity in excess of that required to fill the chambers, means for directing said excess outwardly of the chambers and toward the periphery of the turntable after the chambers have been filled, said excess rotating with the turntable about said axis back to the filling station and means for closing the bottoms of said measuring chambers at least while they are passing through the filling station.

21. A machine in accordance with claim 20 in which the means for urging the material into the chambers is at least one material directing member at the filling station closely overlying the surface of the turntable.

22. A machine in accordance with claim 20 in which the means for urging the material into the chambers is at least one material directing member at the filling station closely overlying the surface of the turntable, and the means for directing the excess outwardly of the chambers after they have been filled comprises a knife beneath which the open tops of the chambers pass.

23. A machine in accordance with claim 20 in which the means for directing the excess outwardly of the chambers is a knife rotatable on a vertical axis closely overlying the open tops of the chambers as they move through their path of travel and a deflecting member contiguous to the upper surface of the knife.

24. A machine for packing materials in containers comprising, in combination, a material receiving turntable rotatable about a vertical axis, a series of material receiving measuring chambers having vertical sidewalls and open tops and bottoms rotatable with said turntable, means for rotating said turntable and chambers continuously through an endless path of travel part of said path including a filling station, said turntable having an annular surface flush with the open tops of the chambers and encircling said chambers upon which at least part of the material to be packed is deposited, means at the filling station for urging the material on the turntable into the chambers, the material being supplied to the turntable and chambers in a quantity such that an excess is always available to insure that the chambers will be filled, means for closing the open bottoms of said chambers at least while they

21

are passing through the filling station, means for positioning a container in alignment with each of said chambers, a plunger above and in alignment with each of said chambers, means for moving said plungers into said chambers to discharge the material therefrom and a trimming knife beneath which the open tops of the chambers pass for removing any material which may overlie the tops of the chambers after they have been filled.

25. A machine in accordance with claim 24 in which the trimming knife is rotatable about a vertical axis and a member overlies the trimming knife and directs the trimmed and excess material toward the periphery of the turntable so that it cannot reenter filled chambers and instead rotates with the turntable back to the filling station.

26. A machine in accordance with claim 24 in which the urging means is an assembly which is oscillatable about the same vertical axis as the turntable rotates and includes a blade extending from adjacent the periphery of the turntable toward the path of the rotation of the chambers and a member which overlies the path of travel of the chambers and has a surface which faces their open tops and presses the material into the chambers for the purpose of filling voids.

27. A machine for packing materials in containers comprising, in combination, a material receiving turntable rotatable about a vertical axis, a series of material receiving measuring chambers disposed in a circle around said axis and rotatable with said turntable, said chambers having vertical side walls and open tops and bottoms and said turntable having an annular surface flush with the open tops of said chambers and extending completely around the circle of chambers and extending completely around the circle of chambers, means for rotating said turntable and chambers continuously through an endless path of travel part of said path including a chamber filling station and part including a container filling station, the material brought to the machine for packing being at least partly deposited on the turntable and being always available at the filling station in an amount in excess of that required to fill the chambers, means at the filling station for urging the material into the chambers, the material tending to mound up over the tops of the chambers, a circular trimming knife between the chamber filling station and the container filling station, said trimming knife being mounted on a vertical axis and having its plane of rotation substantially flush with and overlying the open tops of the chambers so that any ma-

22

terial mounded up over the tops of the chambers is trimmed off, means for rotating said trimming knife, a member overlying the trimming knife for directing excess material and trimmed material toward the external part of the turntable surface and away from said chambers so that said material is prevented from entering the chambers which have been filled and trimmed at least until after the filled and trimmed chambers have passed through the container filling station, means for closing the open bottoms of said chambers while they pass through the chamber filling station and beneath the trimming knife and until they reach the container filling station, a plunger in alignment with each of said chambers and rotatable about the same axis, means for moving containers into a position below said chambers and in alignment therewith, and means for raising and lowering said plungers, said plungers being clear of the tops of the chambers during the chamber filling and trimming operations and being lowered into the chambers to discharge said material from the chambers into the containers at the container filling station.

25. 28. A machine in accordance with claim 27 in which the urging means is at least one blade extending from adjacent the periphery of the turntable toward the path of rotation of the chambers and closely overlying the rotating surface thereof and means adjacent the end of the filling station having a surface overlying the path of rotation of the chambers for pressing the material into the chambers to fill voids.

35. 29. A machine in accordance with claim 27 in which the urging means is an assembly which is oscillatable about the same vertical axis as the turntable rotates and includes a blade extending from adjacent the periphery of the turntable toward the path of the rotation of the chambers and a member which overlies the path of travel of the chambers and as a surface which faces their open tops and presses the material into the chambers for the purpose of filling voids.
